CLAIM

The ornamental design for a vacuum extractor seal tool cover, as shown and described.

DESCRIPTION

FIG. 1 is a front, right and top perspective view of a vacuum extractor seal tool cover, showing my design.

FIG. 2 is a front, right and top perspective view of an upper part of the vacuum extractor seal tool cover of FIG. 1.

FIG. 3 is a rear, left and bottom perspective view of the upper part of FIG. 2.

FIG. 4 is a front elevation view of the upper part of FIG. 2.

FIG. 5 is a rear elevation view of the upper part of FIG. 2.

FIG. 6 is a left side elevation view of the upper part of FIG. 2.

FIG. 7 is a right side elevation view of the upper part of FIG. 2.

FIG. 8 is a top plan view of the upper part of FIG. 2.

FIG. 9 is a bottom plan view of the upper part of FIG. 2.

FIG. 10 is a front, right and top perspective view of a lower part of the vacuum extractor seal tool cover of FIG. 1.

FIG. 11 is a rear, left and bottom perspective view of the lower part of FIG. 10.

FIG. 12 is a front elevation view of the lower part of FIG. 10.

FIG. 13 is a rear elevation view of the lower part of FIG. 10.

FIG. 14 is a left side elevation view of the lower part of FIG. 10.

FIG. 15 is a right side elevation view of the lower part of FIG. 10.

FIG. 16 is a top plan view of the lower part of FIG. 10.

FIG. 17 is a bottom plan view of the lower part of FIG. 10.

FIG. 18 is another front, right and top perspective view of the lower part of FIG. 10 in another state.

FIG. 19 is another front, right and top perspective view of the lower part of FIG. 10 in another state; and,

FIG. 20 is another front, right and top perspective view of the lower part of FIG. 10 in another state.

The broken lines shown in the drawings are included for the purpose of illustrating portions of the vacuum extractor seal tool cover that form no part of the claimed design.

1 Claim, 20 Drawing Sheets
